CLOCK

Charles A. McLeod, Oak Park, Ill., assignor to Sunbeam Corporation, Chicago, Ill., a corporation of Illinois

Filed May 13, 1964, Ser. No. 79,963

Term of patent 14 years

(Cl. D42—7)

Fig. 1.

Fig. 2.

Fig. 3.

FIG. 1 is a front perspective view of a clock showing my new design;

FIG. 2 is a top plan view thereof;

FIG. 3 is a side elevational view thereof;

FIG. 4 is a rear elevational view thereof;

FIG. 5 is a cross-sectional view thereof taken on line 5-5 of FIG. 1; and

FIG. 6 is a cross-sectional view thereof taken on line 6-6 of FIG. 2.

I claim:
The ornamental design for a clock, as shown.
